BRIDGE SUPPORT FOR BI-FOCAL GLASSES

Richard R. Castor, 164 Roselawn Crescent,
Fairport, N.Y. 14450

Filed Feb. 24, 1969, Ser. No. 15,912

Term of patent 14 years

Int. Cl. D16—08

U.S. Cl. D57—1

FIG. 1.

FIG. 2.

FIG. 3.

FIG. 1 is a side elevation view of a bridge support for bi-focal glasses showing my new design;

FIG. 2 is a front elevation view thereof; and

FIG. 3 is a perspective view thereof, the spectacles and facial features being shown in broken lines for illustrative purposes only.

I claim:

The ornamental design for a bridge support for bi-focal glasses, as shown and described.
